UNITED STATES PATENT OFFICE.

THOMAS McAVITY STEWART, OF MONTREAL, QUEBEC, CANADA, ASSIGNOR TO
T. McAVITY & SONS LIMITED, OF ST. JOHN, NEW BRUNSWICK, CANADA.

CAPACITY BLOCK FOR INSPIRATORS.

Application filed July 5, 1921. Serial No. 482,427.

To all whom it may concern:

Be it known that I, THOMAS McAVITY STEWART, a subject of the King of Great Britain, and resident of the city of Montreal, Province of Quebec, Dominion of Canada, have invented certain new and useful Improvements in Capacity Blocks for Inspirators; and do hereby declare the following to be a full, clear, and exact description of the same.

This invention refers to inspirators for supplying feed water to boilers, especially to the "Hancock" type of inspirator which includes a lifter device having a lifter nozzle through which steam is passed into a lifter tube to create a suction to draw the water into the inspirator for conveyance to a forcer device having a forcer nozzle through which steam is passed into a forcer tube to force the water from the inspirator to the boiler. A normally closed forcer steam valve is employed and gradually opened to admit steam initially to the lifter nozzle to start the operation of the inspirator and subsequently admit steam to the forcer nozzle when an adequate quantity of water has been drawn into the inspirator, a normally open overflow valve being simultaneously operated to gradually close an overflow opening in correspondence to the opening of the steam valve, the function of the overflow valve arrangement being to establish a priming current of water through the inspirator to initiate the operation of the forcer device.

This type of inspirator is capable of supplying varying quantities of water in a given time, for example from 2500 to 5000 gallons per hour, being adapted to be alternately fitted with sets of lifter and forcer nozzles and tubes of varying sizes to alter the capacity of the inspirator in accordance with requirements. Inasmuch as an inspirator fitted for a given supply capacity calls for a longer priming period than one fitted for a reduced supply capacity and vice versa, the travel of the overflow valve is varied in correspondence to the capacity for which the inspirator is fitted, a longer travel of such overflow valve being established when the inspirator is fitted for an increased capacity. This adjustment of the travel of the overflow valve is effected by supporting the valve in open position at varying distances from its seat through the medium of

a slidably mounted support held by a block termed a capacity block, the thickness or depth of the block determining the distance between the valve and its seat. A set of separate blocks varying in depth to correspond to varying injector capacities is utilized to vary the travel of the overflow valve, such blocks being separately employed and when an inspirator is fitted for a given capacity, a block of the proper depth to establish that travel of overflow valve requisite for the given capacity, is affixed.

My invention appertains particularly to capacity blocks or equivalent devices utilized for the variance of the travel of valves, the invention having for its object to improve such devices and avoid the disadvantages inherent in their use as previously constructed. Heretofore said capacity blocks have been individually invariable, that is made of a depth for one capacity only, a set of separate blocks being required for a range of capacities, there being usually about five blocks of different depths required for a range of from 2500 to 5000 gallons per hour. Consequently when the capacity of an inspirator is changed the block formerly used has to be removed and another block affixed in accordance with the new capacity. This necessity complicates the refitting of an inspirator and furthermore necessitates the keeping in stock of numerous blocks to meet the different requirements. As these inspirators form part of a locomotive equipment, stocks of the blocks have to be maintained in the widely scattered roundhouses and repair shops of a railway system and if in refitting a locomotive the particular block for the desired capacity is not available serious delay results.

My invention consists in the provision of a device which is individually variable for establishing varying valve travel or a device which is universal in its adaptation to all capacities of a given range formerly requiring several separate capacity blocks, thus enabling an inspirator capacity to be changed without recourse to the removal of one capacity block and its replacement by another block and so avoiding the loss of time resulting from such replacement and obviating the above mentioned disadvantages applying to the use of separate capacity blocks.

The above object with resultant features

will be hereinafter more fully explained and particularly pointed out in the appended claims.

For full comprehension, however, of my invention reference should be had to the accompanying drawings forming a part of this specification, in which the same reference characters indicate like parts and wherein:

10 Fig. 1 is a vertical longitudinal section of a locomotive inspirator embodying my improved capacity block;

15 Fig. 2 is a fragmentary plan view of the mounting for the overflow valve operating lever;

Fig. 3 is a perspective view of the capacity block removed; and

Fig. 4 is a perspective view of the block with the discs separated.

20 In the drawings, 2 indicates the casing of an inspirator, 3 the steam inlet with main and auxiliary steam valves 4 and 5 respectively, 6 the water inlet and 7 the water outlet, the lifter nozzle and lifter tube being 25 respectively shown at 8 and 9 and the forcer nozzle and forcer tube at 10 and 11 respectively. The final overflow opening located at 12 is controlled by final overflow valve 13 while the intermediate overflow opening 14

30 is controlled by intermediate overflow valve 15. The steam and final overflow valves are operated by a lever 16 fulcrumed at 17 to the casing and having the spindle of the steam valve pivoted thereto at 18, the final 35 overflow valve being connected to the lever 16 through the medium of a link 19 and elbow lever 20 fulcrumed at 21 and connected to the stem 22 of the final overflow valve at one end and to the link at the other.

40 The operation of the inspirator is clearly detailed in United States Patent No. 492,944, March 7, 1893, and therefore it will be sufficient for this disclosure to explain that a movement of lever 16 in the direction of the arrow, initially opens auxiliary valve 4, admitting steam to nozzle 8, thence to tube 9 and therefrom to outlet 12 through tube 11 and through port 14 by automatically opening valve 15. This passage of steam through

45 the inspirator creates a suction drawing water from inlet 6 into the casing and through tubes 9 and 11 and port 14 to final overflow opening 12, thus priming the inspirator so that upon continued movement

50 of lever 16 to open main steam valve 4 the steam is passed through nozzle 10 and tube 11 to finally force the water from outlet 7 to the boiler. The movement of lever 16 to gradually open the steam valves 4 and 5

55 acts, through the link 19 and lever 20 to simultaneously gradually close the final overflow valve 13, the adjustment being such that valve 13 closes upon such opening of valve 5 as to establish a proper current 60 through tube 11 to adequately feed the water

to the boiler. The intermediate overflow valve 15 is automatically closed by gravity and the pressure established by the closing of the final overflow valve, such pressure acting upon the top of the valve 15 to close it against its opening pressure.

The above structure is not new but is covered in part by the hereinbefore mentioned patent and is adapted to be fitted with varying sizes of nozzles 8 and 10 and tubes 9 and 11 to vary the supply capacity of the inspirator in gallons per hour, the larger the nozzles and tubes the greater the supply capacity. This variance in the supply capacity of the inspirator necessitates a corresponding variance in the travel of the final overflow valve 13 as a longer priming period and consequently a longer valve travel to delay the closing of the valve is required to establish an adequate forcing current through forcer tube 11 when the inspirator has been fitted with larger nozzles and tubes for an increased supply capacity and likewise a shorter travel of the valve 13 is required when the capacity supply is decreased. Heretofore this adjustment of the travel of valve 13 has been effected by carrying the fulcrum pin 21 of the elbow lever 20, in the lugs 23 of a split sleeve or fulcrum bracket 24 slidably mounted upon a cylindrical post 25 upon the casing 2, the sleeve being moved along the post to position the valve through the lever 20 and stem 22, at such distance from its seat as to provide a travel according to the requirements of the supply capacity of the inspirator fittings.

The sleeve has been moved into suitable position and maintained therein by an arm 26 carried upon the pin 21 at its upper end and bearing at its lower end upon the top of a capacity block (not shown) interposed therebetween and the top of the casing, such block being of a predetermined depth or thickness to position and maintain the sleeve and the fulcrum pin carried thereby at the distance from the valve seat 12 required by the capacity fittings of the inspirator, a change of fittings necessitating the removal of the block then in place and the affixing of a separate block of a depth corresponding to the new fittings. A bolt 27 passes loosely through the arm 26 and capacity block and engages the casing to hold the members in position.

As hereinbefore explained, the present invention consists in means for adjusting the sleeve 24 and through it the position of the final overflow valve with respect to its seat and the consequent travel of such valve, by means of a device which is individually variable to effect the change without removal and replacement so that a universally adaptable intact device may be provided to take care of all adjustments requisite for a given range of capacities.

While it is to be understood that the desired result can be achieved in various ways, the most suitable arrangement at the present time avoids change to existing construction of inspirator in all but one respect, namely the capacity block which, instead of being a block of a fixed depth or thickness is made extensible and capable of adjustment to vary its thickness or depth by forming the block preferably of co-operating parts provided with steps of varying heights whereby the engagement of the parts through the medium of one step produces a block the height of which varies with respect to the height secured by engagement of the parts through the medium of a different step. A block is thus provided which is capable of universal adaptation with respect to varying inspirator capacities within a given range. In the illustrated form the improved capacity block comprises a pair of co-operating members, the opposing surfaces of which have engagement surfaces at varying depths throughout the thickness of the combined members. Such members constitute a block the thickness of which is dependent upon the particular abutment surfaces engaged.

In the form of block I prefer to use the members of the block are constituted by circular discs 28 and 29 respectively, and centrally apertured at 30 to receive the bolt 27. The discs are combined to form a block, the opposing faces of the discs presenting axial lugs 31 spaced circumferentially of the discs, the space between the lugs of disc 28 being occupied by a series of radial faces 32 graduated in depth axially of the disc and extending from one lug to another circumferentially of the disc to form series of steps duplicated between each two lugs and with the radial faces or ends of such lugs forming the highest steps. By nesting the two discs together with the ends of the lugs of disc 29 engaging the lowermost steps of disc 28, the two discs form a rigid block of a certain minimum thickness, which thickness can be gradually increased step by step until the ends of the lugs of both discs engage to produce a rigid block of a certain maximum thickness. The provision of the steps 32 at different depths throughout the axial line or thickness of disc 28 from the outer face of the disc to the end of the lugs 31 thereof, enables the total thickness of the two part block to be varied by a relative circumferential movement of the discs, each step establishing the depth of block necessary for securing adjustment of the final overflow valve in correspondence with a certain inspirator supply capacity. For example the the first or lowermost step of the illustrated block establishes a capacity block thickness for 2500 gallons per hour and the other steps increase the capacity block thick-

ness up to that required for 5000 gallons per hour, the steps being appropriately marked as shown upon the periphery of the disc, figures representing the hour gallons each step corresponds to being placed adjacent such steps.

The capacities encountered usually range between 2500 and 5000 gallons per hour and this range heretofore necessitated the provision of five separate blocks which the illustrated single block of improved construction replaces.

The block is affixed to the inspirator between the arm 26 and top of the casing 2 and held in position by the bolt 27 which passes through the apertured lower end of arm 26 and through the apertures 30 of the discs into screw-threaded engagement with the casing 2. By partially unscrewing the bolt sufficient freedom is secured to permit of a relative movement of the discs 28 and 29 whereby the proper adjustment thereof can be made to secure a depth of block necessary for the particular capacity for which the inspirator is fitted, tightening of the bolt securing the parts in adjusted position. Different depths of block can be secured for subsequent changes in fittings by merely loosening the bolt without removing the latter, thus avoiding the possibility of misplacement of the bolt.

From the above it will be seen that an intact device is maintained affixed to the inspirator and capable of adjustment to establish the desired travel of the valve without recourse to the time taking and inconvenient removal and replacement of separate capacity blocks of fixed depths. The herein described adjustable mounting of the valve support furthermore eliminates the necessity for maintaining numerous stocks of invariable capacity blocks as one device of the improved form is capable of adjustment for adaptation to all capacities usually encountered.

What I claim is as follows:

1. The combination with a valve and its seat, of means for moving the valve to and from the seat and individually adjustable means for supporting the valve at varying distances from said seat to vary the travel of such valve.

2. The combination with a valve and its seat, of means for moving the valve to and from its seat and means for supporting the valve at a certain predetermined distance from the seat when the valve is open, such means being individually adjustable to vary the distance between the seat and valve in its open position.

3. The combination with a valve and its seat, of means for moving the valve to and from its seat, such means including a lever and a fulcrum for the lever and means for supporting said fulcrum at a predetermined

distance from the seat, said means being individually adjustable to vary the distance between the seat and fulcrum.

4. The combination with a valve and its seat, of means for moving the valve to and from its seat, such means including a lever and a bracket to which the lever is fulcrumed, and a support for said fulcrum bracket to hold the bracket at a predetermined distance from the valve seat, said support being individually adjustable to vary the distance between the bracket and valve seat.

5. The combination with a valve and its seat, of means for moving the valve to and from its seat including a lever and a bracket to which the lever is fulcrumed, and an extensible support for said fulcrum bracket to hold the bracket at varying predetermined distances from the valve seat.

6. The combination with a valve casing, a valve and a seat for the valve, of means for moving the valve to and from its seat and means for supporting the valve at varying predetermined distances from its seat, such means including a movable member connected to the valve and supported by the casing, and a block of variable thickness disposed between said member and the casing.

30 7. The combination with a valve casing, a valve and a seat for the valve, of means for moving the valve to and from its seat and means for supporting the valve at varying predetermined distances from its seat, such means including a movable member connected to the valve and supported by the casing and a block disposed between said member and the casing, such block including two co-operating relatively movable members presenting engaging faces at varying points throughout their combined maximum depth.

45 8. The combination with a valve casing, a valve and a seat for the valve, of means for moving the valve to and from its seat and means for supporting the valve at varying predetermined distances from its seat, such means including a movable member connected to the valve and supported by the casing and a block disposed between said member and the casing, such block including two co-operating discs relatively movable circumferentially of each other, one of said discs presenting circumferentially arranged steps spaced axially of the disc and the other disc presenting a lug adapted to alternately engage said steps to vary the depth of said block.

50 gage said steps to vary the depth of said block.

9. In an inspirator, a steam valve, a final overflow valve, an operating lever connected to the steam valve, an angle lever connected to the final overflow valve, a link between the angle lever and operating lever, a bracket slidably mounted upon the inspirator and having said angle lever fulcrumed thereto, an arm extending from the fulcrum bracket and a block disposed between the arm and inspirator, said block being adjustable to vary the thickness thereof.

10. In an inspirator, the combination with a steam valve, removable lifter and force nozzles and tubes of predetermined capacity, such nozzles and tubes being adapted to be replaced by other nozzles and tubes of different predetermined capacity, a final overflow valve and means for simultaneously opening the steam valve and closing the final overflow valve, of means for adjusting the travel of the final overflow valve in correspondence to the requirements set up by the capacity of the nozzles and tubes, said means including a movable support for the final overflow valve and a capacity block disposed between said support and the casing of the inspirator, said block being adjustable to variable thicknesses to hold the support at varying predetermined positions, the various thicknesses of the block corresponding to the various capacities of the nozzles and tubes and being identified therewith upon the block.

11. A capacity block for inspirators and comprising co-operating relatively movable members presenting engaging faces at varying points throughout their combined maximum depth.

12. A capacity block for inspirators and comprising co-operating discs relatively movable circumferentially of each other, one of said discs presenting circumferentially arranged steps spaced axially of the disc and the other disc presenting a lug adapted to alternately engage said steps to vary the depth of said block.

In testimony whereof, I have signed my name to this specification, in the presence of two subscribing witnesses.

THOMAS McAIVITY STEWART.
